CRAYON HOLDER

Gunnard P. Peterson, Naugatuck, Conn., assignor
to The Rison Manufacturing Company, a corporation of Connecticut

Application August 4, 1933, Serial No. 683,590

15 Claims. (Cl. 206—56)

The invention relates to holder-containers for cosmetic crayons and other material of like manner of use, the object being the general improvement of such devices in respect of compactness, ruggedness and appearance.

In the drawings which illustrate the preferred form of the invention,

Fig. 1 is a perspective elevation of the device approximately life size;

Fig. 2 is a longitudinal section of line II—II of Figure 1, greatly enlarged for sake of clarity;

Fig. 3 is a partial longitudinal sectional view at right angles to Figure 2;

Fig. 4, a section on IV—IV of Fig. 3;

Fig. 5, an elevation of the rotary sleeve;

Fig. 6, the flat blank of which it can be formed;

Fig. 7, an elevation of the main or outer cylinder;

Fig. 8, a partial cross-section showing the thumb piece and its keeper;

Fig. 9 a similar view of the inner cylinder.

The outside cylinder being in the present case the enamelled or ornamental casing of the device is marked 1 and is a hollow cylinder which may be conveniently drawn out of brass stock.

It is provided with a longitudinal slot 2 for a traveller button or thumb piece 3 which is retained in the slot by a small curved plate or keeper 4, see Fig. 8. When the cylinder is held in the fingers, the button 3 can be pushed back and forth with the thumb, being thus a "one hand" device. The casing is shown detached in Fig. 7.

Next within the casing or main cylinder 1 is an inner rotary sleeve 5 connected to the button 3 by its spiral slot 6 so that the rectilinear movement of the button 3 rotates the sleeve relatively to and within the main cylinder 1.

Next within the rotary sleeve 5 is an inner cylinder 7 (Fig. 9) which is expanded at its base and there secured in a permanent manner to the base end of the outer casing 1. The junction of these two cylinders is covered over by a cap 8 which constitutes the bottom end closure and reinforcement of the device. It can be a pressed fit thereon as indicated. The rotary sleeve 5 rotates in the annular space between the two united cylinders 1 and 7 and is retained against excessive endwise movement therein by a stud 9 riveted in the inner cylinder 7 and engaging an arcuate slot 10 in the lower part of the rotary sleeve 5. This rotary sleeve can be made of a flat sheet or blank, punched as shown in Figure 6 and rolled to the cylindrical form indicated by Figure 5, the meeting edges

of the blank being locked together by the tongue and notch formation indicated by 11 and between them forming another spiral slot, presently referred to as the slot 16.

Next within the fixed sleeve 7 is the sliding cup or carrier 12 which holds the crayon 13 in any suitable way as for example by friction, the crayon being merely pressed into the cup when the holder is open. The carrier is merely an open ended tube with one or more indent tabs 12^a punched and bent out of its wall to form a seat for the crayon. It is provided with a stud 14 riveted thereto and adapted to ride in the longitudinal slot 15 formed in the inner fixed cylinder 7 and this stud 14 projects through the straight slot 15 into a second spiral slot 16, also formed in the rotary sleeve 5, this being the slot formed by the proximate edges of the rolled blank. The rotation of sleeve 5 moves the carrier up and down, the carrier being held against rotation by its stud engagement with the slot 15 of the relatively fixed cylinder 7. Preferably downward movement of the thumb piece 3 rotates the sleeve 5 in the direction to raise the carrier toward the open end of the holder although this arrangement is not essential and could be reversed if desired and other forms of thumb-operated members could be provided for converting the thumb movement into rotary movement of the sleeve.

The closure mechanism of the holder is of the disappearing door type and comprises two quarter-spherical thin shelves or stampings 17 and 17^a which are duplicates of each other and pivoted inside the holder to swing toward and from each other on a common transverse axis. The end of the outer cylinder 1 is spherically tapered or indent at its end to form a curved annular flange 1^a which somewhat reduces the diameter of the open end of the cylinder. The two door members house under this flange when opened, their paths of movement being close to and substantially concentric with the spherical taper. While the door members may be otherwise mounted and otherwise operated, it is preferred to pivot their hub portions on the two upstanding posts 18 which rise from the upper end of the inner cylinder 7 and these pivots are conveniently formed as eyelets 19, integrally stamped or drawn out of the material of the posts 18 themselves. Each door member hub is cut or stamped with a pair of gear teeth marked 20 and 20^a respectively and these teeth directly overlie the top edge of the rotary sleeve 5 and are arranged to be engaged by corresponding 55

teeth 21 and 21^a cut in such top edge, there being two teeth 21 on one side of the sleeve, and two, 21^a, on the other. The doors and their teeth are punched out of relatively thin sheet stock and the combined thickness of their hubs is about equal to that of the sleeve. The teeth are arranged in such manner that rotation of the sleeve swings the two members toward or from each other, closing them together on the center line of the device, and opening them to positions under the flange 1^a. The doors are opened by the initial movement of the sleeve 5 after which one of the teeth on each door member rides along on the smooth top edge of the sleeve, thus holding the member open. On return of the sleeve to its initial position, the door teeth are picked up again by the sleeve teeth and thereby restored to closed position. This action is timed so that the doors are open 20 at the proper point to permit the crayon to protrude and are closed after it has receded through the door opening.

While it is desirable that the door segments shall operate close to the inner face of the spherical flange 1^a thus to make a tight dust-excluding closure, it is also important that they shall not rub or bind thereon at least to such an extent as to interfere with their free action and make the device difficult to operate. Such binding effect unless prevented is likely to occur from distortion, under the pressure of the user's thumb of the casing 1. This as well as the other cylinders are made of the thinnest practical section for the sake of lightness of weight, and economy of material, the rotary sleeve being the thickest member on account of its teeth and the work it has to perform. Such distortion is guarded against according to this invention, in part by the spherical taper or flange 1^a which stiffens the casing 1 and in part by giving such casing one or more points of internal support. Three of such supports are represented by the pimples 22, which are punched in the rotary sleeve 5 and two other points may be provided by allowing contact of the casing upon the upset ends of the pivot eyelets 19 on the posts 18. The base end of the casing 1 is stiffened by the inner cylinder as well as by the cap 8. In this way a very light 50 outer casing, of uniform diameter from end to end, may be employed and even though slotted for nearly its full length without danger of such distortion as would impose an excessive friction either on the door members or on the keeper 55 4 of the sliding thumb piece, which latter must slide freely at all times in the annular crevice between the outer cylinder and the rotary sleeve, or as would disalign the door members from proper relation to the door-opening or 60 their operating gearing.

The device above specifically disclosed represents, as stated, the preferred form of the invention, but the principles embodied therein will be seen to be capable of use separately and in 65 combination in various different kinds and forms of holder-containers within the scope of the claims which follow and except as set forth in the claims, no limitation to the form described is intended.

70 I claim:—

1. A device of the kind described comprising an outer cylinder of constant diameter from end to end but having its wall at one end indent to form an annular flange and a doorway of 75 reduced diameter, an inner cylinder spaced from

said outer cylinder but fixed thereto at the base end thereof, so as to reinforce the base of the outer cylinder against deformation, a door member for said doorway operating within said flange, and means at the door end of said inner cylinder to support said outer cylinder, said outer cylinder having a longitudinal slot and a thumb-piece therein for operating said member. 5

2. A device of the kind described comprising a hollow outer shell flanged or curved at one end to form a doorway, an inner cylinder fixed in said shell, a curved door member pivoted on the inner cylinder and within the flange of the outer shell, said inner cylinder providing a supporting bearing to support the outer shell 10 against deformation, a carrier, and a slide button in a slot in the outer shell connected for 15 operating said member and carrier.

3. A device of the kind described comprising a hollow cylinder of constant diameter but 20 spherically tapered at one end to form a doorway, an inner cylinder fixed in the outer cylinder, a spherically curved door member mounted on the inner cylinder within the tapered end of the outer cylinder to close the doorway, and 25 a plurality of points of internal support for supporting the door end of said cylinder against binding on said door member and a slide button working in a slot in the cylinder for 30 operating said members.

4. In a device of the kind described, an outer cylinder having a doorway, coacting door members therefor transversely pivoted within the doorway, an internal rotary sleeve for rotating such members on their pivots, a longitudinally 35 moving thumbpiece on the cylinder engaging a spiral slot in said sleeve for rotating it, and means engaging said sleeve for retaining it against longitudinal displacement toward said 40 piece.

5. A device of the kind described, comprising three concentric cylinders, one of which is rotary and located between the other two, a slide button operating in a slot in the outer cylinder and engaging a spiral slot in the rotary cylinder, a carrier reciprocating in the innermost cylinder and provided with a stud engaging slots in both said inner cylinder and said 45 rotary cylinder, a door member operated by said rotary cylinder and a slot in said rotary cylinder cooperating with a relatively fixed stud for restraining it from endwise movement.

6. In a device of the kind described, an inner cylinder having mutually coacting door members hinged thereto, an outer casing fastened to 55 said cylinder at its base end and having a supporting bearing on said cylinder at the door end, a thumb-piece sliding in a slot in said outer casing, and means for transmitting the thumb- 60 piece movement to said door members.

7. A device of the kind described, comprising three concentric cylinders, one of which is rotary relatively to the other two, a pair of transversely pivoted door members within the outer 65 cylinder adapted to close the end thereof, a button sliding in a slot in the outer cylinder and engaging a spiral slot in the rotary cylinder, a reciprocating carrier provided with a stud engaging slots in said rotary cylinder and one of the relatively fixed cylinders and gear-tooth connections between said rotary cylinder and both said door members.

8. In a device of the kind described, a hollow casing or cylinder of constant diameter but in- 75

- wardly curved at one end to form a doorway, two coating door members therefor concentrically mounted within said doorway, and a sleeve within said cylinder having gear tooth 5 connections at its end with said two door members respectively on opposite sides of the axis of the device.
9. In a device of the kind described, an outer casing or cylinder, an inner relatively rotary cylinder having gear teeth on opposite sides thereof at its end and pivoted coating door members respectively engaged by said teeth and simultaneously turned in opposite directions thereby.
10. In a device of the kind described, relatively rotary concentric cylinders, a pair of stamped metal door members pivoted on a common axis on one of said cylinders and having gear teeth, the other cylinder having oppositely arranged gear teeth respectively engaging with said door member teeth to move said members in opposite directions by the unidirectional relative rotation of said cylinders, the edge of said toothed cylinder between its said teeth being smooth for holding said members stationary in their open position and the wall thickness of said toothed cylinder being substantially equal to twice the thickness of said door members.
11. In a device of the kind described, an outer casing and an inner cylinder fixed at its base thereto, a rotary sleeve between said casing and cylinder of thicker section than either of them, teeth cut in the upper edge of said sleeve and a pair of coating door members formed as stampings and having registering hubs pivoted on a common axis above said sleeve and teeth cut on said hubs meshing with the thicker teeth on said sleeve, and adapted to open said door member by the relative rotation of said sleeve.
12. In a device of the kind described, the combination of inner and outer concentric and relatively rotary cylinders, the inner cylinder having pivoted thereto two coating and oppositely moving door members and the other cylinder having gear tooth engagement with each of said members respectively on opposite sides of the axis of the device.
13. A device of the kind described, comprising concentric cylinders the walls of which are close together, each being substantially contiguous to the next, the innermost cylinder forming a crayon carrier, the outer cylinder being longer than any intermediate cylinder and of constant diameter from end to end except that it is tapered or incurved to a reduced diameter at its open end to form a doorway having a diameter substantially equal to that of the crayon carrier, two door members for said doorway, transversely pivoted on one of said cylinders and geared to an intermediate cylinder and located to house themselves when open in the annular space under the incurved part of the outer cylinder and around the path of the carrier cylinder, and a single means for conjointly reciprocating said carrier cylinder back and forth and said door members toward and from each other.
14. In a device of the kind described, a main casing having a pivoted door to close its end, a spirally-slotted rotary sleeve therein geared to open said door by its rotation, said sleeve being formed of a flat blank rolled to cylindrical form and provided with interfitting tongue and notch formation between its meeting edges when so rolled and rectilinearly moving means engaged in the spiral slot of said sleeve.
15. A device of the kind described comprising an outer casing of substantially cylindrical form from end to end except that it is tapered at one end to form a doorway of reduced diameter, a slide button working in a slot in said casing, a rotary sleeve in said casing formed with oppositely pitched spiral slots, one of said slots engaging said slide button, and a reciprocating carrier in said sleeve having a stud member engaged by the other of said spiral slots, a door member for said doorway and means whereby the relative rotation of said sleeve operates said door member.

GUNNARD P. PETERSON. 45
